United States Patent Office

Des. 213,947
Patented Apr. 29, 1969

213,947

PANTY GIRDLE

Harry Dubner, New York, N.Y., assignor to Milady Brassiere and Corset Co., Inc., New York, N.Y., a corporation of New York

Filed May 14, 1968, Ser. No. 11,919

Term of patent 14 Years

Int. Cl. D2—02

U.S. Cl. D2—4

FIG. 1

FIG. 2

FIG. 3

FIG. 4

FIG. 1 is a front perspective view of a panty girdle, showing my new design;

FIG. 2 is a rear perspective view thereof;

FIG. 3 is a front perspective view of a modified form of the design shown in FIG. 1; and

FIG. 4 is a rear perspective view thereof.

I claim:

The ornamental design for a panty girdle, substantially as shown and described.
